ATTORNEYS

UNITED STATES PATENT OFFICE.

ARTHUR JOHNSON, OF NEW YORK, N. Y.

DESIGN FOR A LAPEL-BUTTON.

No. 38,361.

Specification for Design.

Patented Dec. 18, 1906.

Application filed November 13, 1906. Serial No. 343,305. Term of patent 7 years.

To all whom it may concern:

Be it known that I, ARTHUR JOHNSON, a citizen of the United States, and a resident of the city of New York, borough of Manhattan, in the county and State of New York, have invented a new, original, and ornamental Design for a Lapel-Button, reference being had to the accompanying drawing, in which the figure is a plan view of a lapel-button, showing my new design.

I claim—

The ornamental design for a lapel-button as shown.

ARTHUR JOHNSON.
